CASH REGISTER

Joseph J. Klosterman, deceased, late of Dayton, Ohio, by Mary Klosterman, executrix, Dayton, Ohio, assignor to The National Cash Register Company, Dayton, Ohio, a corporation of Maryland

Original application September 30, 1940, Serial No. 359,047. Divided and this application May 23, 1942, Serial No. 444,223

3 Claims. (Cl. 235—3)

This invention relates to printing mechanism for cash registers and like machines, and more particularly to control means therefor, and is a division of the application for Letters Patent of the United States Serial No. 359,047, filed by Joseph J. Klosterman, on September 30, 1940, which issued into Patent No. 2,342,082 on February 15, 1944.

The invention is disclosed as embodied in the key-operated type of machine such as that shown in United States Letters Patent No. 2,279,805, granted April 14, 1942, to Frank R. Werner, and in the application of Daniel K. Hughes for United States Letters Patent, Serial No. 273,231, filed May 12, 1939, which issued into Patent No. 2,338,942 on January 11, 1944.

An object of the present invention is to provide novel means to connect and disconnect the printer unit driving means with and from the main operating means of the machine.

Another object is to provide a plurality of manipulative devices to control said connecting and disconnecting of the printer driving means with and from the main operating means.

A further object is to provide a novel locking means intermediate said manipulative means.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In said drawing:

Fig. 1 is an elevation of a portion of the left side of the receipt printer unit, showing the driving means and the disabling means for the driving means.

Fig. 2 is a detail, partly in section, of the paper feed drive shaft and the means for controlling its movement.

Fig. 3 is a detail of the locking mechanism for the paper feed drive shaft.

Fig. 4 is a front view, partly in section, of the paper feeding mechanism.

Fig. 5 shows the means to control the locking means for the connecting means between the main drive and the printer drive.

Fig. 6 is a detail of the hammer operating mechanism.

Fig. 7 is a detail of the paper compression or feed rolls.

GENERAL DESCRIPTION

Described in general terms, this divisional ap-

plication deals with a printing mechanism which prints and issues receipts or checks to be given to customers with purchases of goods.

However, in some instances, it is desirable that a check be not issued, such as when Read and/or Reset operations are performed, and, to accomplish this result, there is provided means to disconnect the printing mechanism, including the impression means and the feeding means, from the main operating mechanism.

Such controlling means includes a manually operable member by means of which the printer driving means may be entirely disconnected from the main driving means.

A second manually operable device, however, is provided to determine when said manually operable member can be operated to effect its control of the printer driving means.

DETAILED DESCRIPTION

Printer frame

As has been fully illustrated and described in the parent application, the printer is built in a unit so that it may be bodily removed from the machine. However, in this divisional application, the manner of mounting this printing mechanism is not shown, as it has not been thought necessary for this application.

The printing mechanism dealt with in the present divisional application is supported by a left printer plate 60 and a right printer plate 61 (Figs. 1, 4, and 6), which are supported by rods 22 and 64 (Fig. 1) carried by the machine side frames (not shown in this divisional application).

Type wheels

The parent application illustrates and describes three amount type wheels, one transaction type wheel, and one clerk's type wheel for printing upon the issuing check. However, in the present divisional application, only one type wheel is shown in Figs. 1 and 6. It is the units type wheel 69. This type wheel 69 is carried on shaft 68, supported by plates 60 and 61, and it is differentially set under control of the 5¢ key and the 10¢ to 90¢ keys of the parent application. In the home position, this wheel 69 presents a zero to the printing line and a "5" when the 5¢ key is depressed. When a key in the 10 to 90 group ending in zero is depressed, the wheel 69 again presents a zero to the printing line, but when a key in the 10 to 90 group ending in "5" is depressed, then the wheel 69, through means illustrated and described in the parent case, presents a "5" to the printing line.

Paper feed mechanism

Referring to Fig. 1, a paper roll 130 rests on a curved plate 131, the rear end of which is turned over a rod 132 supported between the printer plates 60 and 61. The front end of the plate 131 has claws 133, only one being shown, which grip a rod 134 supported by the plates 60 and 61. The front of the plate 131 is formed into a paper chute 135, through which a paper strip 136 led from the roll 130 is carried over the type wheels and between the paper feed rolls 137 (Fig. 4) and the compression rolls 138. The compression rolls are rotatably supported by a shaft 139 (Figs. 1 and 7) flexibly supported between two stationary claws 140 (only one of which is shown) and an opposed resiliently mounted claw 141 between the two claws 140.

The claws 140 (Fig. 7) are secured to a yoke 142 carried by the arms 143 (only one of which is shown), which are pivotally mounted on the rod 134 so that the yoke and the compression rolls may be moved towards and away from the paper strip 136. The resiliently mounted claw 141 has a tongue 145 slidably mounted in a hole in a cover plate 146 attached to the yoke 142. A spring 147 holds the claw 141 against the shaft 139, which in turn is held against the claws 140. If the compression rolls are moved toward the paper while rocking the yoke, they resiliently meet the paper strip 136 and hold it against the feed rolls 137.

An arm 148 (Fig. 1) is pivotally mounted on one arm of the yoke 142 and has a finger piece 149 and a locking arm 150. This arm 150 has arcuate surfaces 151 and 152 adapted to engage a stud 153 carried by the printer plate 61. The surface 151 locks the yoke 142 in closed position, and, as shown by the dot-and-dash lines in Fig. 1, the surface 152 locks the yoke 142 in open position for the free insertion of the leading end of the paper roll between the feed rolls 137 and the compression rolls 138. Fastened to the plate 146 is a serrated tear-off knife 158.

In Fig. 6 is shown a printing platen 154 for cooperating with the type wheel 69. This platen is carried as a yoke by the arms 155 and 160 rotatably mounted on the rod 134.

Referring to Figs. 2, 3, and 4, the paper feed rolls 137 are pinned to the shaft 157 journaled in bushings 161 and 162 secured in the printer plates 60 and 61. Fastened to the shaft 157 is a ratchet 163, which cooperates with a pawl 164 pivoted on a stud 165 projecting from the printer plate 60 and resiliently held by a spring 166 against the ratchet 163 to prevent counter-clockwise movement of the shaft 157. A second pawl 167, pivotally mounted on the main drive shaft 91 of the printer, cooperates with the ratchet 163 to prevent clockwise movement of the shaft 157. The spring 166, being connected to the pawl 167, holds this pawl resiliently against the ratchet 163, but it is arranged so that the pawl 167 is pushed away to an ineffective position by a stud 168 (Fig. 1) carried by a driving segment 169 for the feed rolls. This driving segment 169 is secured to the main drive shaft 91, and, as the latter is rocked clockwise, the stud 168 rocks the pawl 167 (Fig. 3) clockwise as the segment 169 nears the end of the clockwise movement during the first half of the machine operation, as will be described herein-after, thus releasing the pawl 167 from the ratchet 163 and freeing the shaft 157 for movement. The drive segment 169 receives movement from a link 170 pivoted thereto, which is given movement

to the right (Fig. 1) as a key coupler 171 is raised by depression of any key. The coupler 171 is lowered to the position shown during the second half-operation of the machine, thus moving the drive segment 169 counter-clockwise to the position shown in Fig. 1.

The movement of the key coupler 171 is transmitted to the link 170 by means of a plate 172 pivoted on a shaft 173 through the medium of a stud 174, to which the link 170 is hooked. A pinion 175 loosely mounted on the shaft 157 is therefore driven first counter-clockwise and then clockwise as the driving segment 169 makes its oscillatory movement.

On its counter-clockwise movement, the pinion 175 rotates free of the shaft 157, but, on the clockwise movement thereof, a pawl 176 (Fig. 2), pivoted on a plate 180 integral with the pinion 175, engages an opening in a rim 177 of a flanged plate 178 secured to the shaft 157, thereby rotating the shaft 157 clockwise and carrying the paper strip 136 forwardly, or to the right as viewed in Fig. 1. This forward movement of the paper strip occurs after mid-cycle, at which point the printing impression is made.

By the above ratchet-and-pawl construction, this feed mechanism is unidirectional, prevents retrograde motion of the paper strip, and determines the exact amount of paper advance on each machine operation.

Disabling mechanism for the main drive to the printer

The means for disabling the connecting or operating means between the main driving means and the printer driving means, whereby the paper feeding mechanism and the hammer operating mechanism may be rendered ineffective for certain kinds of operations, will now be described.

A link 170 (Fig. 1) forms a connection between the main operating means, which includes the coupler 171 and the operating plate 172, and the driving means or segment 169 for operating the printer, including the paper feeding and hammer operating mechanism. The link 170 is pivoted to the segment 169 and the forward end thereof is hooked over the stud 174 on the main driving plate 172, so that it may be disconnected therefrom for certain types of operations.

This link 170 has a slot 181, which accommodates a stud 182 on one arm of a bell crank 183 pivotally mounted on the main drive shaft 91. The other arm of the bell crank 183 carries a stud 184, which projects into a cam slot 185 of a link 186 slidably mounted by means of slots 187 and 188 on the shaft 91 and a shaft 113, respectively.

With the parts in the positions shown in Fig. 1, the link 170 is positively connected to the main driving member 172. However, when it is desired to disable the printing mechanism, including the paper feed and impression means, the link 186 is moved rearwardly, or to the left as viewed in Fig. 1, whereupon the cam slot 185, through the stud 184, rocks the bell crank 183 clockwise, causing the stud 182 to rock the link 170 clockwise and disengage its hook from the stud 174.

Movement of this link 186 to the left, however, is normally blocked by means of the stud 191 contacting an unbroken portion of the flange on a wheel 189, which is secured to the shaft 113.

This wheel 189 is cut away, as shown at the broken portion 190, and the flange thereof is also cut away, and consequently, when this broken portion 190 of the flanged wheel 189 is presented

opposite the stud 191, the link 186 may be moved to the left to disconnect the link 170 from the stud 174 to disable the printing mechanism.

The means for moving the wheel 189 to present the broken-away portion 190 to the stud 191 consists of a manually operable lever 114 (Fig. 5) pivoted on a stud 115. This lever 114 is provided with teeth meshing with a pinion 117 secured to the shaft 113.

With the lever 114 in the position shown in Fig. 5, the wheel is in the position shown in Fig. 1, but when the lever 114 is rocked counter-clockwise into the "read" position or the "reset" position indicated in Fig. 5, the shaft 113 is rotated counter-clockwise to position the broken portion 190 of the wheel 189 opposite the stud 191, so that the link 186 may be moved to the left to disconnect the link 170 from the driving member 172.

The means for moving the link 186 to the left as described above includes an "on and off" manipulative disk 192 (Fig. 1), which is secured to the shaft 122. Also secured to the shaft 122 is an arm 193 carrying a stud 123 projecting in a slot 124 in the link 186.

The manipulative disk 192 is shown in the "on" position, but, when this link is moved manually in a clockwise direction, the arm 193 and the stud 123 move the link 186 to the left to disconnect the paper feed mechanism and the impression mechanism from the key coupler 171 and the operating plate 172.

Therefore, during "read" or "reset" operations, the paper feeding mechanism and the impression mechanism may be rendered inoperable if desired.

If the lever 114 is moved back to the position shown in Fig. 5 after the link 186 has been moved to the left, then the inner periphery of the flange of the wheel 189 will encircle the stud 191 and lock the link 186 in the left-hand or "off" position, whereby the paper feeding means and the impression means will not be operated during adding or item-entering operations.

The control lever 114 has a key lock 319 (Fig. 5) on its forwardly projecting arm to lock it in one of five positions indicated by chain lines in Fig. 5.

Impression or printing hammer drive

The means for driving the hammer or impression means from the driving segment 169 will now be described.

As this segment 169 is driven first clockwise and then counter-clockwise (Figs. 1 and 6), its motion is transmitted by the link 214 to the lever 215 pivoted on the rod 134. A trigger lever 216 is pivoted to the top of the lever 215 by a stud 220 carried by a lever 219, and is normally held by a spring 217 against a set screw 218 mounted in said lever 219. An arm 221 of the lever 219 carries the stud 222, which projects into a cam slot 223 in a link 224 pivoted to the lever 215 by a stud 225 at one end and pivoted at the other end to a stud 226 on a lever 227, which is pivotally mounted on a stud 228 in the printer frame 69.

The cam slot 223 is so shaped that, as the lever 215 is rocked counter-clockwise, the lever 219 and the lever 216 are rocked slightly counter-clockwise relatively to the lever 215. The hammer yoke arms 155 and 160, the lever 215, and a hammer driving lever 237 are all mounted on the rod 134. As the lever 215 is rocked counter-clockwise, a rearwardly extending arm of the arm 230 of the trigger lever 216 engages a flange 229

of the lever 237, which flange lies in a notch 231 of the hammer arm 160 and forces the platen 154 to rock counter-clockwise around the rod 134 against the increased tension of a spring 232 fastened to a stud 233 on the lever 227 and to a stud 234 on a pivoted lever 235 at its other end.

A spring 236 holds the printer hammer arm 160 against the flange 229 of the lever 237 until the inertia of the printing movement of the hammer on its release, after being cocked, overcomes the strength of the spring 236, whereupon the hammer is allowed to overthrow a sufficient amount to strike the paper to take an impression from the type wheel.

Now, to continue with the cocking of the printing hammer as the printer lever 216 moves relatively to the lever 215 due to the action of the cam slot 223, a shoulder 238 of the trigger lever 216 slips off the flange 229, and the spring 232 rocks the hammer forcefully in a clockwise direction, which movement continues until the end of the overthrow; as explained above.

A shoulder 239 on the lever 235 strikes a stud 240 on the overthrow of the hammer and cushions the shock, as the hammer hits the paper and the type wheels, by stretching the spring 232. At the end of the hammer blow, the spring 236 rocks the hammer back to home position, so that the platen 154 is slightly off the paper.

Operation

Since the operations of the mechanism involved in this divisional application have been described in detail, it is not thought necessary to describe the operation of the mechanism further. However, from the above description, it can be very clearly seen that, through the operation of the manipulative device, the main driving mechanism may be disconnected from the printing means, whereby the paper feeding mechanism and the hammer operating means will not function, and that such operations can be controlled through the medium of a second manually operable device which, when set in certain positions, prohibits the operation of the first mentioned manipulative means, which directly controls the printing means by disconnecting its drive from the main drive.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described capable of adding and total printing operations and having impression means, feeding means, an operating member for both of said means, main operating means, and a coupling link to normally couple the operating member to the main operating means, the combination of manipulative means operable to disconnect the coupling link from the main operating means; a device normally blocking movement of the manipulative means; a manually movable control means to control certain elements of the machine for adding and total printing operations; and connections between said manually operable control means and the device whereby said control means adjusts the device out of blocking position, when the control means is moved to a total printing position, to release the manipulative means

whereby the manipulative means may be manipulated only when the control means is in total printing position.

2. In a machine of the class described capable of adding and total printing operations and having impression means, feeding means, an operating member for both of said means, main operating means, and a coupling link to normally couple the operating member to the main operating means, the combination of manipulative means operable to disconnect the coupling link from the main operating means; a device normally blocking movement of the manipulative means; a total printing control lever to condition certain elements of the machine for printing totals; a key lock for the total control lever; and means operated by the total control lever to move the blocking device out of normal blocking position to release the manipulative means, so that an authorized operator may unlock the total control lever to release the manipulative means and thereafter move the manipulative means to disconnect the link from the main operating means.

3. In a machine of the class described capable of adding and total printing operations and having impression means, feeding means, an operating member for both of said means, main operating means, and a coupling link to normally

couple the operating member to the main operating means, the combination of a manipulative device; an element having a cam means therein and connected to the manipulative device for movement therewith; a lever coacting with the cam means and the link whereby the link is moved to be disconnected from the main operating means to disable the impression means and the feeding means; a notched disk normally in position to prevent movement of the element to normally prevent disabling of the impression means and the feeding means; and a total control lever having a normal position and a total control position operatively connected to the notched disk to move the notched disk into a position to release the element upon movement of the total control lever out of the normal position into a total control position, whereby the manipulative device may be manipulated to move said cam means and thereby move said link out of said normal coupling position to uncouple the impression means and the feeding means from the main operating means, only when the total control lever is in said total control position.
